BATTERY PACK

Lawrence Victor Merrill, Brooklyn, N. Y., assignor
to Mears Radio Hearing Device Corp., New
York, N. Y., a corporation of Delaware

Application May 16, 1941, Serial No. 393,771

3 Claims. (Cl. 136—173)

This invention relates to improvements in hearing devices for deaf persons and those whose hearing is affected.

An object of the invention is the provision of improvements in a hearing device which render it more adaptable for the use, convenience and comfort of a person requiring such device.

A further object of the invention is the provision for a hearing device of a battery pack affording an electrical energy input to a microphone of the vacuum-tube audio-amplifier type, and also affording an electrical energy output to a suitable receiver constituting a part of the device.

A further object is the provision of a battery pack of the indicated character which is designed and adapted for direct connection with and to serve as a support for a microphone of the type mentioned, or which, by the use of an extension cord, may be remotely connected with said microphone if desired.

A further object is the provision of a battery pack for a hearing device which is compact, and one which accommodates batteries or cells of different sizes as to length to meet different voltage requirements.

With the foregoing and other objects in view, the invention resides in the combinations, constructions and functions of the parts as defined in the appended claims, described in the following specification and illustrated in the accompanying drawing, in which

Fig. 1 is a vertical sectional view of a battery pack and microphone, the latter being shown partly in section and a portion thereof being broken away, and a pack carrier being shown in dot-and-dash lines;

Fig. 2 is a top plan view of the battery pack itself;

Fig. 3 is a sectional view, the section being taken approximately on the line 3—3 of Fig. 1 and looking in the direction indicated by the arrows;

Fig. 4 is a sectional view, the section being taken approximately on the line 4—4 of Fig. 1 and looking in the direction indicated by the arrows;

Fig. 5 is a sectional view, the section being taken approximately on the line 5—5 of Fig. 1 and looking in the direction indicated by the arrows;

Fig. 6 is a sectional view, the section being taken on the line 6—6 of Fig. 1 and looking in the direction indicated by the arrows;

Fig. 7 is a view of an extension cord used in

conjunction with the battery pack and microphone.

In the drawing there are shown a battery pack 10, a transmitter or microphone 11 and an extension cord 12, these being involved in the present invention. The microphone 11 is of the vacuum-tube audio-amplifier type, and when mounted on the pack 10 in electrical connection therewith the pack furnishes an electrical energy input to the microphone and also furnishes an electrical energy output to a suitable receiver constituting a part of a hearing device. When it is desired to associate the microphone 11 remotely from the pack 10, use is made of the extension cord 12, in which case the pack 10 will furnish an electrical energy input to the microphone while the extension cord 12 affords the electrical energy output to the aforesaid receiver.

The battery pack 10 includes a substantially rectangular flat plate 13 of insulating material, such as fibre, Bakelite, or hard rubber. An upper contact plate 14 is fixedly secured to the upper end of the plate 13 so as to project laterally at a right angle with respect thereto and for this purpose said plate 14 has depending lugs 15 and 16 integral with the plate 14 and arranged in spaced relation with respect to each other. Fastening elements, such as screws 17, extend through holes respectively in the lugs 15 and 16 and are driven into the plate 13. The plate 14 has a hole 18 therein, the wall of which is beveled or flared downwardly. This plate 14 constitutes a positive contact. Below the plate 14 at a suitable distance is detachably secured a U-shaped spring 19 consisting of spaced parallel portions 20 and 21 which are connected by an intermediate portion 22. Each of the portions 20 and 21 is L-shaped. The spring 19 is held in place by fastening elements 23 and 24, which are received in eyes respectively provided by the portions 20 and 21 and extending through holes respectively in the plate 13 and having nuts to securely fasten the elements to said plate. The elements 23 and 24 constitute binding posts. It is to be understood that the spring 19 is made of conducting material, such as spring wire stock. A lower contact 25 of a generally Y-shape is developed from a single piece of conducting metal to provide a pressure member 26, axially aligned eyes 27, and retaining lugs 28. The intermediate portion 22 of the spring 19 extends through the eyes 27, by virtue of which the contact 25 is pivotally connected with the spring 19. Normally the portion of the spring 19 which extends laterally with respect to the plate 13 is disposed at an acute angle with

respect thereto in order to make the contact 25 cooperate effectually with the contact plate 14 when a battery, such as the "A" battery 29, is arranged between the same. The battery 29 may be set in place by bringing the lower end thereof in engagement with the lugs 28 and then exerting a downward pressure on the battery to cause the spring 19 to yield sufficiently so that the positive terminal 30 of the battery is engageable in the hole 18. The member 26 of the contact 25 will press on the casing of the battery 29, which is the negative pole. Consequently, the contact 25 is a negative contact.

A substantially L-shaped contact 31 having a cam 32 is rigidly secured to the upper end of the plate 13 on the side thereof opposite that on which the plate 14 is disposed. The contact 31 is held in place by screws 33 driven into the plate 13. The contact 31 is of metal having the proper degree of resiliency. This contact 31 is the positive contact. An L-shaped contact 34 having a cam 35 is secured to the plate 13 by screws 36. This contact 34 is of metal having the desired resiliency and is the negative contact. The contacts 31 and 34 cooperate to detachably support a "B" battery 37. The battery 37 may be moved side-wise into position against the cams 32 and 35 engaged by the upper and lower ends respectively of the battery, causing the contacts to flex sufficiently and then to reflex so that the contact 31 engages the opposite pole and the contact 34 engages the negative pole of the battery 37.

The battery pack 10 also includes a head 38 of insulating material, such as Bakelite, hard rubber, or any other suitable material. The head 38 is oblong and has an oblong recess 39 in the top and an oblong recess 40 in the bottom. The head 38 is rigidly secured in place over the partition plate 13, contact plate 14 and contact 31, by means of screws 41 extending through holes in the plate 14 and driven into the head 38 from the under side. The head 38 carries electrical terminals 42, 43, 44, 45 and 46 respectively, which are disposed upright in a row spaced from each other. The terminals have their lower threaded ends screwed into the head 38 and are similar in cross-sectional size and length, with the exception of the terminal 42 which is longer than the others and has its lower end screwed into the plate 14 so as to make electrical connection therewith. The terminals rise from the recesses 39. It will be apparent that the terminal 42 being in threaded engagement with the plate 14 and the latter being in engagement with the positive pole 30, is electrically connected with the battery 29.

One end of a flexible conductor 47 is soldered or otherwise secured as at 48 to the contact 34, extends through a hole 49 in the plate 13, and passes upwardly with its opposite end soldered or otherwise secured to the lug 15 as at 50. Current, therefore, flows from the "B" battery 37 through contact 34, conductor 47, plate 14 and terminal 42. This terminal 42 is therefore an A+ B- terminal. There is an electrical connection 51 between the contact 31 and the terminal 43 and it is, therefore, a B+ terminal. An electrical conductor or wire 52 has one end thereof connected with the binding post 23 and its opposite end connected with the terminal 44 and it is, therefore, an A- terminal. The terminals 42, 43 and 44 as connected with the batteries 29 and 37 constitute means for furnishing an electrical energy input to the microphone 11 when connected therewith as shown in Fig. 1.

In accordance with another feature of the invention electrical sockets 53, 54 and 55 respectively are secured to and extend through the head 38. The sockets 53 and 54 are arranged on the right side of the head, while the socket 55 is arranged on the left side of the same. Each of the sockets projects into the recess 40. An electrical conductor or wire 56 has the opposite ends thereof connected with the terminal 45 and the socket 53 respectively. An electrical conductor or wire 57 has the opposite ends thereof connected with the terminal 43 and the socket 54 respectively. If desired, this connection may be made directly to the terminal 43 or by joining it to the conductor 51. An electrical conductor or wire 58 has the opposite ends thereof connected with the terminal 46 and socket 55 respectively. The microphone 11 has five electrical sockets corresponding to the terminals 42, 43, 44, 45 and 46 to receive the same to establish electrical connection in order that the electrical energy input will be furnished to the microphone as stated above, and the terminals 43 and 45 as connected with the sockets 54 and 53 constitute means to furnish an electrical energy output from the microphone 11 to a suitable receiver when the terminals thereof are plugged into the sockets 53 and 54. This is resorted to when use is made of a high impedance receiver. When a low impedance receiver is used the terminals thereof are plugged into the sockets 54 and 55 respectively to obtain the sound output from the microphone 11.

As shown in Fig. 1, the microphone 11 is mounted directly on the battery pack in electrical connection therewith to constitute a single unit to be carried on the person. However, when it is desired for the sake of convenience and greater comfort, the microphone is remotely connected with the battery pack by the use of the extension cord 12 shown in Fig. 7. This cord has a multiple socket 59 on one end to receive the terminals 42, 43, 44, 45 and 46, and the other end of the cord 12 has a multiple plug 60 having five terminals corresponding to the terminals 42, 43, 44, 45 and 46 receivable in the sockets of the microphone 11. When the cord 12 is used the terminals 61 and 62 of a receiver are plugged into suitable sockets in the plug 60 to contact the audion terminals in order to furnish a sound output from the microphone to the ear-piece of a high impedance receiver. In case a low impedance receiver is used the terminal 62 is plugged into the socket 55.

In order to accommodate batteries of different lengths the plate 13 has extra holes 63 extending therethrough to receive the fastening elements 23 and 24 to mount the spring 19 and parts connected therewith at a lower position, as indicated in dotted lines in Fig. 1. Also extra holes 64 in the plate 13 accommodate the screws 36 respectively to mount the contact 34 lower down, as indicated in dotted lines in Fig. 1.

The plate 13 and head 38 constitute a structure of substantially T-shape which serves for compactly supporting two batteries, means for detachably engaging and retaining the batteries in place, the terminals and sockets together with conducting means leading from said engaging means to the terminals and sockets. The provision and arrangement of parts constitute a compact and unitary device which is designed and adapted for direct connection with and serves as a support for the microphone of the hearing device.

It is to be understood that the battery pack 10

will be arranged in a suitable open top receptacle or case, shown in dot-and-dash lines in Fig. 1 and said receptacle being designated 65. When the battery pack is arranged in the receptacle 65 only the head 38 and parts carried thereby will be disposed above the upper end thereof, as clearly shown.

I claim:

1. In a battery pack, an insulator, a fixed contact on said insulator, a U-shape wire spring consisting of spaced parallel bent portions connected by an intermediate portion, part of said bent portions extending laterally with respect to said insulator; means connecting said bent portions to said insulator to secure the spring in place, a 15

contact pivotally connected with said intermediate portion whereby said last contact is resiliently mounted to cooperate with said fixed contact to detachably support a battery cell with the terminals thereof in electrical connection with said respective contacts.

2. In a battery pack as defined in claim 1, wherein said means constitute binding posts as well as a securing means for said spring.

3. In a battery pack as defined in claim 1, wherein said resiliently mounted contact has portions for engaging the side and also the bottom respectively of said cell.

LAWRENCE VICTOR MERRILL.
